US0D1014003S

(12) United States Design Patent (10) Patent No.: US D1,014,003 S
(45) Date of Patent:  Feb. 13, 2024

(54) SHAWL

(71) Applicant: Ramon Estany Bufill, Barcelona (ES)

(72) Inventor: Ramon Estany Bufill, Barcelona (ES)

() Term: 15 Years

(21) Appl. No.: 29/782,347

(22) Filed: May 6, 2021

(30) Foreign Application Priority Data

Dec. 23, 2020 (EM) 008367973-0001

(51) LOC (14) Cl. 02-05

(52) U.S. Cl.

USPC D2/500

(58) Field of Classification Search

USPC D2/500, 501, 502, 503, 504, 505, 506,

..... D2/507, 508, 603, 604, 605, 865

CPC A41D 23/00; A41D 2200/20; A42B 1/04;

..... A42B 1/18; A42B 5/00; A41G 5/0093

See application file for complete search history.
